UNITED STATES PATENT OFFICE.

BENJAMIN WOLHAUPTER, OF NEW ROCHELLE, NEW YORK.

REINFORCED RAIL-ANCHOR.

1,279,817.

Specification of Letters Patent. Patented Sept. 24, 1918.

Application filed August 29, 1917. Serial No. 188,811.

To all whom it may concern:

Be it known that I, BENJAMIN WOLHAUPTER, a citizen of the United States, residing at New Rochelle, in the county of Westchester and State of New York, have invented certain new and useful Improvements in Reinforced Rail-Anchors, of which the following is a specification.

This invention relates to the subject of rail anchors designed to prevent longitudinal creeping of railroad rails, and particularly to a reinforced construction for devices of this character.

As is well known, a rail anchor must possess certain characteristics to satisfy the exacting demands imposed thereon. One of these characteristics is that the device must be so constructed and arranged that it may, in effect, become substantially a rigid part of the rail so that longitudinal movement thereof will be effectually resisted by engagement of the anchor with a rigid abutment, such as the tie at the same time taking up as little space as possible to avoid contact with the ballast. This requirement, in rail anchor construction, also involves the practical necessity of having the strength of the device properly distributed without an undue increase in the weight and size thereof.

With these conditions in view, the present invention primarily contemplates a reinforcement for rail anchor construction which provides maximum strength and stability with a minimum use of metal. It is therefore a distinctive object of the present invention to provide a reinforced rail anchor device possessing the desirable characteristics of lightness and minimum weight coupled with maximum strength throughout.

With these and other objects in view which will be apparent to those familiar with the art the invention consists in the novel features of improvement hereinafter more fully described, illustrated and claimed.

The essential feature of the invention, involved in an I-bar formation of rail anchor body, is necessarily susceptible of structural modification without departing from the scope of the invention, but certain preferred and practical embodiments of the device are shown in the accompanying drawings, in which:

Figure 1 is a side view of a rail anchor having incorporated therewith the improve-

ment of the present invention, and shown in its applied position on the base of the rail.

Figs. 2, 3, and 4 are cross sectional views, respectively on the lines 2-2, 3-3, and 4-4 of Fig. 1.

Fig. 5 is a plan view of the rail anchor structure shown in Fig. 1.

Fig. 6 is a side elevational view of a spring-clip type of rail anchor embodying the present invention and showing a variation in the distribution of metal.

Figs. 7, 8, and 9 are cross sectional views respectively on the lines 7-7, 8-8 and 9-9 of Fig. 6.

Fig. 10 is a plan view of the rail anchor structure shown in Figs. 6 to 9 inclusive.

Fig. 11 is a detail elevational view of another form of reinforced rail anchor constructed in accordance with the present invention and shown applied to the base of a rail.

Fig. 12 is a cross sectional view on the line 12-12 of Fig. 11.

Fig. 13 is a similar view on the line 13-13 of Fig. 11.

Fig. 14 is a top plan view of the form of anchor shown in Fig. 11.

Similar reference characters designate corresponding parts throughout the several figures of the drawings.

As indicated, a distinctive feature of the present invention is the provision of an adequately reinforced rail anchor structure possessing the desirable characteristic of lightness, while at the same time having the metal distributed therein in such a manner as to provide a maximum reinforcing effect where it is most needed. This permits the anchor to withstand the severe service conditions to which it is subjected, without impairing its hold upon the rail.

To this end, it is proposed, according to the present invention, to utilize as a basis of construction an I-bar distribution of metal for the body of the anchor. That is to say, in carrying forward the present invention, the body of the anchor, regardless of its rail engaging or rail gripping features, is constructed on the principle of an I-bar. This design of bar provides a most effective distribution of metal, while at the same time admitting of a relatively light construction. In other words, with the same amount of metal the I-bar formation pro-

vides a stronger device and a relatively greater load-carrying and force-resisting capacity than the rectangular shape of bar commonly used in making structures of this kind. Also, an I-bar shape affords opportunity, with even a decrease of weight, to transpose the metal from the side areas of the bar within the neutral zone to the top and bottom portions thereof with the advantageous result of placing reinforcement on the bar where most needed to better resist the strains and loads imposed upon it. This reinforcement also enables the bar to be clamped upon the rail to an extreme degree of tightness without danger of breaking or fracturing the bar.

By way of illustrating the application of the I-bar distribution of metal to the construction of a rail anchor, there is shown in Figs. 1 to 5 inclusive of the drawings a clip-type of rail anchor adapted to be forcibly driven upon the wedge-like rail flange, and held thereon by the spring gripping force produced through the distortion of the clip when forced into place. The spring-clip type of rail anchor, selected for illustration in the group of figures referred to, primarily consists of a resilient clip body 11 having upper and lower spring clamping jaws 12 and 13 respectively, one of said jaws being provided with a pair of gripping elements 14-14, and the other jaw being provided with a single gripping element 15, this particular structure being reversible as will be readily apparent. Furthermore, it will be observed that one of said jaws is preferably provided with a bowed portion B having at approximately the terminals of its arc or bow the projecting gripping elements 14-14 referred to, so that the device will have a more effective gripping action by reason of providing a three-point contact with the rail flange. In this structure, it will be seen that the opposite members 12 and 13 of the spring clip constitute spring clamping jaws which are intended to have a direct gripping or biting engagement with both the upper and lower surfaces of the rail flange, and when the clip is driven on to the wedge-shape rail flange there will be a tendency of the bowed portion B to flatten out more or less, resulting in augmenting the biting engagement of the elements 14-14 as the clip is crowded inwardly upon the flange.

The clip-type of structure above described may be most advantageously made of a bar of high-carbon steel suitably tempered and which has an I-bar distribution of metal, namely, a relatively thin web portion *a* and oppositely extending flanges *b* connected by the web portion and combining therewith to provide a bar of relatively light weight but of maximum strength by reason of the reinforcement given thereto by the flanges along its edge portions. Furthermore, in a rail

anchor of the type shown in Figs. 1 to 5 inclusive a properly graduated distribution of the metal in the bar formation to properly absorb the varied strains to which it is subjected will attain improved results. That is, in a structure of this type the bight of the clip in the region of the section line 3-3, where the greatest strain occurs, on Fig. 1 may be given substantial strength by having the I-bar in this zone of a greater depth and therefore greater strength than elsewhere throughout the bar body, and to so graduate the depth of the girder that it will be of the least depth, relatively, at or adjacent the terminals of its upper and lower jaw members 12 and 13, where the strains are the least. For instance, adjacent the terminal of its upper jaw member 12, within the region of the section line 2-2, the bar formation may be of materially less depth than at the bight of the clip, and the same may also be true of the bar within the region of the section line 4-4. In other words, the clip type of anchor may be constructed of a bar which has a graduated distribution of metal so that it diminishes in depth toward the terminals thereof, and a depth of the girder for the bowed portion B is sufficiently shallow to permit of such bowed portion to have sufficient independent resiliency to enable it to perform the function above indicated. It will also be observed that in the construction described the clip body may be of uniform width throughout the graduating effect, being proportional to the strains and loads to which it is subjected confined to the depth of the girder between its flanges.

By way of exemplifying the range of modification that may be resorted to in applying the principle of an I-bar distribution of metal to a rail anchor bar, reference is made to Figs. 6-10 wherein the bar body or bar is illustrated of uniform depth throughout, but of tapering width toward the gripping end portions of the clip, where the strains are lightest and whereby the bight of the clip may have a sufficiently added body of metal of I-bar formation to materially increase the strength of that part of the clip where the strains are heaviest.

To further illustrate that the invention is susceptible of variation to meet different requirements and adapted to different forms of rail anchors there is illustrated in Figs. 11 to 14 inclusive a different type of anchor and a modification in the I-bar distribution of metal. Referring in detail to this modification, shown in said Figs. 11 to 14 inclusive it will be observed that there is shown in this illustration a spring clamp type of anchor which primarily consists of a bar of spring steel, designated generally by the numeral 16 which is subjected to bending operations to form at one end of the bar a rail engaging clip 17 provided

with upper and lower clip members 18 and 19 respectively, and the lower of which clip members is designed to have a substantial clearance from the rail base and from the outer edge of the rail flange. Also, in this type of anchor the spring bar 16 has formed at an intermediate point an upstanding or bowed portion 20 constituting a fulcrum element adapted to engage the base of the rail, and at one side of this fulcrum element the bar is extended into a lever arm 21 formed at one end with the looped lifting member 22, extending, with a free clearance, about one of the rail flanges and having a top member 23 overlying the rail flange and adapted to be forcibly engaged by an adjustable wedge-key 24 or equivalent tensioning device. This wedge-key 24 is interposed between the under side of the top part 23 of the lifting member 22, and the upper side of the rail flange, and, when driven tightly home, exerts a lifting force on the member 22 and the lever arm 21, with the result of placing the entire bar under spring tension and thereby causing a tight gripping of the rail at the fulcrum element 20 and by the upper clip member 18.

The spring action of the spring-clamp type of anchor 16 is made entirely effective by having the metal of the bar so distributed as to withstand, to any degree within practical limits, a powerful tensioning thereof through the tightening of the wedge-key 24 or equivalent tensioning device. That is, the present invention provides for distributing the metal throughout the anchor body 16 in an I-bar formation, whereby the body of the bar is formed with a relatively thin web *a*, and the oppositely extending flanges *b*. It will thus be seen that the anchor body is provided with substantial reinforcing flanges at both edges and with a relatively thin and light web portion *a* connecting said flanges, and combining therewith to make a relatively light structure having great strength along its edge portions, and at the places where most needed in an anti-creeper device.

In the embodiment of the invention above described, a uniform I-bar distribution of metal is maintained throughout the bar body, that is to say, at any point in the length of the body as shown by Figs. 12 and 13 of the drawings, the section is of uniform size as to all dimensions, depth, width, and thickness.

Other modifications and adaptations of the invention will now be clear to those familiar with the art without further description, and it will be understood that changes in the form, proportion and minor details of construction may be resorted to without departing from the principles or sacrificing any of the advantages of the invention.

I claim:

1. A rail anchor having a resilient body of I-bar formation.
2. A rail anchor having a resilient body portion of I-bar formation, and having rail engaging means. 70
3. A rail anchor having a resilient body portion of I-bar formation, and having rail-base engaging means.
4. A rail anchor having a resilient body portion of I-bar formation, and having rail-flange engaging means. 75
5. A rail anchor including a resilient body having reinforcing elements, and rail engaging elements. 80
6. A rail anchor including a resilient body having reinforcing flanges at its edges, and provided with rail engaging means.
7. A rail anchor including a resilient body having an I-bar distribution of metal throughout, and provided with rail-engaging means. 85
8. A rail anchor including a resilient bar of I-bar formation, and having rail-engaging means. 90
9. A rail anchor including a spring bar of I-bar formation, and having rail-engaging means.
10. A rail anchor including a spring bar having an I-bar distribution of metal throughout, and provided with rail-engaging means. 95
11. A rail anchor including a resilient bar consisting of a relatively thin web and opposite projecting flanges connected by the web, said bar being provided with rail-engaging means. 100
12. A rail anchor including a tapering bar of I-bar formation having rail-engaging means. 105
13. A rail anchor including a bar having an I-bar formation and tapering toward its ends, said bar having rail-engaging means.
14. A rail anchor including a bar of an I-bar formation of graduated depth. 110
15. A rail anchor including a bar of an I-bar formation of graduated depth toward its ends.
16. A rail anchor including a rail-engaging clip having an I-bar formation and tapering in depth toward its ends. 115
17. A rail anchor having a body of I-bar formation and provided with upper and lower clamping jaws.
18. A rail anchor having a body of I-bar formation one end of which clampingly engages the top and the other end of which engages the bottom of the rail flange. 120
19. A rail anchor including a body of I-bar distribution of metal throughout and having a gripping jaw at one end. 125
20. A rail anchor consisting of a single bar of metal of I-bar formation having a jaw at one end.
21. A rail anchor consisting of a single 130

- bar of metal of I-bar formation and having a jaw at one end for gripping the top and bottom of one of the rail flanges. 15
22. A rail anchor comprising a resilient clip of I-bar formation. 20
23. A rail anchor of I-bar formation and having a jaw at one end and a resilient rail gripping member adjacent the other end.
24. A rail anchor having a jaw for gripping the rail when the anchor is secured thereto by a transverse movement, said anchor being of I-bar formation and of varying section whereby the points of
- strongest section correspond with the points of greatest strain.
25. A rail anchor adapted to be applied to a single rail having a body of I-bar formation.
26. A rail anchor including a body of I-bar formation and of tapering width. 20

In testimony whereof I hereunto affix my signature in the presence of two witnesses.

BENJAMIN WOLHAUPTER.
